CLAIM

The ornamental design for an implant having porous surface structure, as shown and described.

DESCRIPTION

FIG. 1 is a top perspective view of an implant having a porous surface structure in accordance with the present invention.

FIG. 2 depicts a region 3 in the implant of FIG. 1 from which FIG. 3 is enlarged.

FIG. 3 is an exploded view of one porous structure for the region 3 depicted in FIG. 2.

FIG. 4 is a top perspective view of an implant having a porous surface structure in accordance with the present invention.

FIG. 5 depicts a region 6 in the implant of FIG. 4 from which FIG. 6 is enlarged; and,

FIG. 6 is an exploded view of a porous structure for the region 6 depicted in FIG. 5.

The broken line showing is included for the purpose of illustrating environment and forms no part of the claimed design.

1 Claim, 6 Drawing Sheets
